No. 761,414.

PATENTED MAY 31, 1904.

W. SECHER & L. W. GREVE.
IMPACT TOOL.
APPLICATION FILED NOV. 30, 1903.

NO MODEL.

UNITED STATES PATENT OFFICE.

WILLIAM SECHER AND LOUIS W. GREVE, OF CLEVELAND, OHIO.

IMPACT-TOOL.

SPECIFICATION forming part of Letters Patent No. 761,414, dated May 31, 1904.

Application filed November 30, 1903. Serial No. 183,089. (No model.)

To all whom it may concern:

Be it known that we, WILLIAM SECHER and LOUIS W. GREVE, citizens of the United States, and residents of Cleveland, county of 5 Cuyahoga, and State of Ohio, have invented certain new and useful Improvements in Impact-Tools, of which the following is a specification, the principle of the invention being herein explained and the best mode in which 10 we have contemplated applying that principle, so as to distinguish it from other inventions.

The annexed drawings and the following description set forth in detail one mechanical 15 form embodying the invention, such detail construction being but one of various mechanical forms in which the principle of the invention may be used.

In said annexed drawings, Figure I represents an axial section of our improved pneumatic impact-tool, showing the plunger in the 20 position in which it has shifted the valve to admit air behind the plunger to drive the same forward or outward; and Fig. II, a similar section with the plunger in its forward position and the valve shifted to admit air in front of the plunger to drive the same back.

The tool has a barrel 1, the bore of which forms the working cylinder. The outer or 25 forward end of this cylinder is formed with a tool-socket 2, in which the shank of the working tool 3 fits and is held by means of a suitable clip 4. The tool may be a chisel, calking-tool, rivet set, or whatever shape of working tool is required for the work to be done by such working tool under impact. A plunger 5 is fitted to reciprocate within the working cylinder. The inner end of the cylinder has an external flange 6 and bears against the 30 forward face of a disk 7, having a central aperture surrounded by a flange 8, which fits into the inner end of the working cylinder. The rear face of this disk bears against the forward face of a cylindrical valve-block 9, against the rear end of which a button 10 35 bears. This button fits in a recess in the bottom of a socket 11, formed upon a closed handle 12. The outside of this handle-socket is screw-threaded, and a longitudinally-split 40 coupling-sleeve 13 has an internal screw-

thread which is screwed upon the thread of the socket and has at its forward edge an internal flange 44, which engages the flange of the barrel. The barrel, disk, valve-block, button, and handle are drawn together by this 45 coupling-sleeve, and the sleeve is tightened to prevent it from turning by tightening screws 14 through outwardly-projecting ears 15 at the edges of the longitudinal split in the sleeve. The handle has screw-socket 16, to which the 50 air-hose may be attached, and an inlet-channel 17 extends from said socket and through the handle to the bottom of the handle-socket, where it forms an annular inlet-recess 18, which is open into the button-recess in the bottom of 55 the handle-socket. The valve-block has an axial valve-chamber 19 in its forward portion, which valve-chamber is of slightly greater diameter than the central flanged opening in the disk. This forward chamber communicates 60 with a chamber 20 of less diameter and extending through the rear end of the valve-block. The button which closes the rear end of the valve-block has a recess 21 in its forward face, which recess registers with the rear end of the 65 small-diameter valve-chamber. A live-air inlet 22 extends through the button and the wall of the valve-block to near the forward end of the same, and a groove 23 in the face of the button connects the recess in the latter to the 70 live-air inlet. The forward end of the live-air inlet-channel 22 communicates with an annular live-air port 24 in the large-diameter valve-chamber immediately to the rear of the flanged disk. An annular distributing-port 75 25 is formed in this valve-chamber to the rear of the inlet-port and communicates through a channel 26 with the forward end of the working cylinder immediately to the rear of the tool-socket, the channel extending through 80 the valve-block and the side of the working cylinder. An annular exhaust-port 27 is formed at the rear end of the large-diameter chamber, and an exhaust-port 28 extends from the annular port through the side of the valve-block 85 into an annular exhaust-chamber 29, surrounding the valve-block and in the handle-socket. One or more exhaust-openings 30 leads from this exhaust-chamber to the outer 90 air through the side of the handle-socket. An 95 100

annular cylinder-exhaust port 31 is formed at the rear of the exhaust-port 27 and in the small-diameter valve-chamber, and said port communicates by a channel 32 through the 5 valve-block and cylinder-wall with an exhaust-port 33 into the working cylinder a distance from the rear or inner end of the latter. An exhaust-port 34 is formed near the outer or forward end of the working cylinder 10 through the wall of the same and leading to the atmosphere and serves as an auxiliary exhaust from that end of the working cylinder for the air in front of the forwardly or outwardly moving plunger. An escape-port 15 35 is formed through the wall of the working cylinder a distance from the forward end of the same and the inner end of the tool-shank slightly in excess of the length of the plunger, so that said port will be uncovered by 20 the plunger when the latter arrives at the forward extreme of its throw to permit the air behind the plunger to escape and the pressure behind the plunger to be reduced. A cylindrical valve reciprocates in the two-diameter 25 valve-chamber and has a long small-diameter piston 36, which fits in the small-diameter chamber, a recess 37 forward of this latter piston, and a short small-diameter piston 38 forward of this recess. A large-diameter piston 39 is formed immediately forward of the short small-diameter piston to close the forward end of the small-diameter chamber when the valve is in its rearward position and to 30 cut off forward communication to the exhaust-port when the valve is in its forward position. The valve has a reduced neck 40 forward of this piston and has a piston 41, which has play at both sides of the live-air inlet-port in the forward end of the valve-chamber. A 35 throttle-valve 42 controls admission of air through the live-air inlet-channel and is operated by a suitable trigger 43.

When live air is admitted into the tool, the channel leading from the inlet-channel to the 45 rear end of the valve-chamber will place live air permanently against the small-diameter rear face of the valve, thus having a permanent tendency to force the valve forward. When the parts are in the positions illustrated 50 in Fig. I, the valve has been forced rearward by the action of the returning plunger upon the air trapped between the rear-end exhaust 55 33 and the forward large-diameter face of the valve, compressing such air, and the valve is held in this position by the pressure of the live air, which is admitted through the uncovered inlet-port into the inner end of the working cylinder and back of the plunger, acting against the large area of the forward 60 end of the valve and overcoming the same pressure against the small-area rear face of the valve. Of course the compressing action of the returning plunger against the large-diameter face of the valve and upon the air

trapped will overcome and be greater than 65 the forward pressure of the normal live air against the small rear area of the valve and will push the valve rearward against this pressure, whereupon the valve will be held in its rear position by the differential action of the live 70 air against the differential faces or areas of the valve. The air entering the inner end of the working cylinder drives the plunger forward, and the advancing plunger drives the air in front of the same out through the auxiliary exhaust and through the distributing-passage 26, whence it exhausts through the distributing-port 25 and the exhaust-port in the valve-chamber. When the plunger arrives at the forward extreme of its throw and 80 strikes the shank of the working tool, effecting its operative blow upon said tool, the plunger uncovers the escape-port in the working cylinder and the live air behind the plunger is thus relieved and the pressure of 85 the same is reduced, so that the constant live-air pressure acting against the small-area face of the valve can force the valve forward against the reduced pressure upon the forward large-area face of the valve, and thus 90 shift the same to accomplish the rearward or inward throw of the plunger. The recess in the valve around the neck of the same connects the forward distributing-channel with the live-air inlet and admits live air forward 95 of the plunger to force the same rearward. The air behind the returning plunger escapes through the rear exhaust-port and channel through the recess in the rear part of the valve and out through the exhaust-port and 100 passages. When the returning plunger has passed the rear exhaust-port, it cuts off exhaust from the rear end of the working cylinder and compresses the air trapped therein until the pressure thus produced overcomes 105 the forward pressure permanently against the rear small-area face of the valve by its action against the large-area forward face of the valve and shifts the valve rearward, when the entire operation of the parts is again repeated. 110

The valve in this tool is thus actuated by constant pressure against one face and intermittent increased pressure of air compressed by the returning plunger. By this actuation 115 of the valve great simplicity of construction and operation of the tool is attained, and the valve is shifted with great rapidity, causing great speed and strength of the blow of the plunger upon the shank of the working 120 tool.

Other modes of applying the principle of our invention may be employed for the mode herein explained. Change may therefore be made as regards the mechanism thus disclosed, 125 provided the principles of construction set forth, respectively, in the following claims are employed.

We therefore particularly point out and distinctly claim as our invention—

1. In an impact-tool of the type described, a valve to control the admission and exhaust to and from the cylinder, said valve being constructed and arranged with a permanent live-air admission against one face to force it in one direction and with an opposed face exposed to air compressed between it and the plunger to force it in the opposite direction.

2. In an impact-tool of the type described, a valve to control the admission and exhaust to and from the cylinder, said valve having differential - pressure areas and having its 15 smaller pressure area exposed to constant live-air pressure to move it in one direction at one stroke of the plunger and being moved in the opposite direction by compression of the air between its large pressure area and the 20 plunger at the return stroke.

3. In an impact-tool of the type described, a valve to control the admission and exhaust to and from the cylinder, said valve having one pressure area permanently exposed to the 25 live-air pressure and having an opposed pressure area exposed to air compressed between it and the returning plunger.

4. In an impact-tool, the combination of a cylinder, a plunger reciprocable therein, inlet 30 and exhaust passages for the motive fluid, and a valve movable in a chamber at one end of the cylinder and serving to control the flow of fluid to and from each end of the cylinder, one face of said valve being permanently exposed to motive-fluid pressure and the other face being exposed to the action of motive 35 fluid compressed by the returning plunger.

5. In an impact-tool, the combination of a cylinder, a plunger reciprocable therein, inlet

and exhaust passages for the motive fluid, and 40 a valve serving to control the flow of motive fluid to and from each end of the cylinder, said valve having one face exposed to the action of motive fluid compressed by the returning plunger and another face permanently 45 exposed to the motive fluid under normal pressure.

6. In an impact-tool, the combination of a cylinder, a plunger reciprocable therein, and a valve controlling the flow of motive fluid to 50 and from each end of the cylinder, said valve having one face exposed to the action of motive fluid compressed by the plunger as the latter approaches one end of its stroke and another face of smaller area and exposed to 55 permanent normal pressure of the motive fluid.

7. In an impact-tool, the combination of a cylinder, a plunger reciprocable therein, a valve-chamber, and a differential piston-valve 60 in said chamber controlling the inlet and exhaust of motive fluid to and from the opposite ends of the cylinder, said valve having a pressure-face exposed to air compressed by the plunger at one end of its stroke to be moved 65 in one direction and having another pressure-face permanently exposed to motive-fluid pressure to be moved in the opposite direction.

In testimony that we claim the foregoing 70 to be our invention we have hereunto set our hands this 19th day of November, A. D. 1903.
